FOREIGN PATENT DOCUMENTS

DE 9415962 1/1994

Primary Examiner — T. Chase Nelson
Assistant Examiner — Kathleen M Sims**(57) CLAIM**

The ornamental design for a wand, substantially as shown and described.

DESCRIPTION

FIG. 1 is an isometric view of a wand according to the present invention;

FIG. 2 is a front elevation view of the wand of FIG. 1;
FIG. 3 is a rear elevation view of the wand of FIG. 1;
FIG. 4 is a left side elevation view of the wand of FIG. 1;
FIG. 5 is a right side elevation view of the wand of FIG. 1;
FIG. 6 is a top plan view of the wand of FIG. 1; and,
FIG. 7 is a bottom plan view of the wand of FIG. 1.
The broken lines represent environmental structure and form no part of the claimed design.**1 Claim, 4 Drawing Sheets**## U.S. PATENT DOCUMENTS
